US0D1087126S

(12) **United States Design Patent** (10) Patent No.: **US D1,087,126 S**
Cao et al. (45) Date of Patent: ** Aug. 5, 2025

(54) **DISPLAY SCREEN OR PORTION THEREOF WITH A GRAPHICAL USER INTERFACE**

(71) Applicant: **Beckman Coulter Biotechnology (Suzhou) Co., Ltd.**, Jiangsu (CN)

(72) Inventors: **Ming Cao**, Liaoning (CN); **Ta Na**, Liaoning (CN)

(73) Assignee: **Beckman Coulter Biotechnology (Suzhou) Co., Ltd.**, Suzhou (CN)

(**) Term: **15 Years**

(21) Appl. No.: **29/880,127**

(22) Filed: **Jul. 18, 2023**

(51) **LOC (15) Cl.** **14-04**

(52) **U.S. Cl.** USPC **D14/486**

(57) **CLAIM**

The ornamental design for a display screen or portion thereof with a graphical user interface as shown and described.

DESCRIPTION

The FIGURE is a front view of a display screen or portion thereof with a graphical user interface.

The outermost dashed lines in the FIGURE show a display screen or portion thereof and a boundary of the claimed design and form no part of the claimed design. The other dashed lines in the FIGURE depict portions of the graphical user interface that form no part of the claimed design.
